LOCKING THREAD MECHANISM

George T. Hart, Jr., Lynn, Mass., assignor to
United Shoe Machinery Corporation, Paterson,
N. J., a corporation of New Jersey

Application October 10, 1930, Serial No. 487,778

8 Claims. (Cl. 112—233)

The present invention relates to the locking thread mechanism of lockstitch sewing machines, and more particularly to the thread case and tension devices of lockstitch shoe sewing machines employing rotary or oscillatory loop taking hooks or shuttles.

An object of the invention is to improve the locking thread mechanism of machines such as that illustrated and described in the patent to 10 Ashworth No. 1,169,909, dated February 1, 1916, for Sewing machine, so as to adapt such machines to use a thread mass or cop which gives up thread from within in place of the bobbin illustrated in said patent. To that end, a feature of the invention consists of a thread case open at its forward end for the reception of a thread cop and having formed in its rear surface a centrally located thread outlet.

A further object of the invention is to provide 20 a thread tension device for oscillatory or rotary shuttles or thread cases which employ thread masses or cops which give up thread from within.

Another object of the invention is to provide 25 a thread cop which will, of necessity, be positioned with its proper surface adjacent the thread outlet of the thread case, and which is provided with a supporting casing to hold it against collapse during the withdrawal of the last few turns of thread on the cop, at which time a cop with 30 no supporting medium tends to collapse. To these ends, the cop is provided with a casing of tin foil or like material about its periphery and upon the surface opposite the thread delivery end of the cop, and the cop as thus encased is of such a diameter that it will fit closely within 35 the thread case, the close fit of the cop within the thread case cooperating with the tin foil casing about the cop to hold the cop against collapse.

Further objects of the invention are to provide 40 a thread tension device which is simple, compact and durable and which enables a fine adjustment of the tension to be secured and in which the parts are securely locked in adjusted 45 position.

With the above objects in view, the invention 50 also consists in the combinations and arrangement of parts hereinafter described and claimed, the advantages of which will be obvious to those skilled in the art from the following description.

In the accompanying drawings, illustrating the 55 preferred form of the invention, Figure 1 is a plan view of the thread case with the tension device applied thereto; Figure 2 is a side view of the same; Figure 3 is a sectional view taken on

the line 3—3 of Figure 1; Figure 4 is a detail view of the tension adjusting device, developed for convenience of illustration; Figure 5 is a detail perspective view of the tension device; Figure 6 is a section on the line 6—6 of Figure 1; 60 and Figure 7 is a sectional elevation of a portion of the lockstitch sewing machine illustrated and described in the patent to Ashworth hereinbefore referred to having embodied therein the 65 thread case and tension device of the present invention.

The body of the thread case is cylindrical in form and comprises a circular wall 8 closed at one end and open at the other end to receive the thread cop. The flange 10, extending partly 70 around the thread case, is provided to engage in the supporting groove 11 in the inner surface of the rotary loop taking hook. The thread outlet is indicated at 12 and is centrally located in the thread case in order to adapt the same to be 75 used in connection with thread cops.

The tension devices comprise a resilient thread 80 engaging finger 14 positioned within a radial opening formed in the thread case and provided with a bevelled surface 15 adapted to cooperate 85 with the bevelled surface 16 formed in the periphery of the thread outlet, said resilient member and bevelled surface together forming a means for applying a yielding pressure to the thread as it passes through the thread outlet. The tension 90 member 14 is pivotally mounted upon the convex surface 18 formed in the thread case, and is loosely held against longitudinal movement by the pin 20 mounted in said convex surface, which pin passes freely through a hole 21 in the tension member 14, sufficient clearance being provided between the pin 20 and the periphery of the hole 21 to permit rocking movement of the tension member upon the convex surface 18. The 95 tension member 14 is turned up at its outer end and has the inclined surface 22 formed at the extremity of the upturned portion thereof. Means for adjusting the thread tension consists of the inclined surface 24 formed in the member 26. The inclined surface 24 is complementary 100 to the inclined surface 22 formed in the tension member 14 and is adapted to slide upon said surface 22 in order to depress the outer end of the tension member 14, thereby increasing the pressure of the tension member upon the thread. The 105 member 26 is slidably mounted in a concentric dovetail groove formed in the periphery of the thread case and is provided with bevelled surfaces 28 adapted to slide in said groove. It is obvious 110 that a movement of the member 26 in the direc-

tion of the arrow in Fig. 2 will depress the outer end of the tension member 14 and increase the pressure of said member upon the thread, and that a movement of the member 26 in the opposite direction will permit the outer end of tension member 14 to rise and thereby lessen the pressure of said member upon the thread.

Means for locking the tension adjusting member 26 in adjusted position consists of a vertical projection 30 formed in one end thereof and adapted to engage alternatively a plurality of perforations 32 formed in the thread case. In order to permit the tension adjusting member 26 to be unlocked and readjusted, the projection 30 is formed in a bifurcation 34 formed in said member 26, the outer end of said bifurcation having a recess or hole 36 formed therein for the reception of an unlocking tool.

The thread mass or thread cop is indicated at 33 in its proper position within the thread case and has the tin foil casing 40 pressed about its periphery and over the surface of the thread cop opposite the thread delivery end thereof. By thus encasing the cop, the thread delivery end of the cop is clearly indicated and the operator must necessarily position the cop in the thread case with the thread delivery end thereof adjacent the thread outlet of the thread case, thereby preventing the twisting and kinking of the locking thread 30 which would result from misplacing the thread cop.

The loop taker is indicated at 42 (see Fig. 7) and is in the form of a tubular hook rotatably mounted upon the plates 44 and 46 secured to the machine frame, and adapted to support the thread case upon its inner surface, the thread case forming a closure for the rear end of the hook. The thread case is permanently mounted in the supporting groove 11 in the hook and consequently 40 the thread cop must be passed through the forward end of the hook and into the thread case. Motion is imparted to the rotary hook 42 through the bevelled gear 48 which meshes with a series of bevelled teeth cut in the periphery of the forward end of the rotary hook. For a more complete description of the rotary hook and its actuating mechanism, reference may be had to the patent to Ashworth hereinbefore referred to.

The nature and scope of the invention having 50 been indicated and a device embodying the features thereof having been specifically described, what is claimed as the invention is:—

1. A locking thread mechanism for sewing machines comprising a cylindrical thread case, a centrally located thread outlet in said case, a thread engaging surface at the periphery of said outlet, a member adapted to compress the thread against said thread engaging surface, and means for imparting a variable pressure to said member consisting of a member slidably mounted in the periphery of the thread case.

2. A locking thread mechanism for sewing machines comprising a cylindrical thread case, a centrally located thread outlet in said case, a thread engaging surface at the periphery of said outlet, a member pivotally mounted in said case and adapted to compress the thread against said thread engaging surface, and means for imparting a variable pressure to said member consisting of a member slidably mounted in the periphery of the thread case.

3. A locking thread mechanism for sewing machines comprising a cylindrical thread case, a centrally located thread outlet in said case, a thread engaging surface at the periphery of said

outlet, a radially positioned member pivotally mounted in said case adapted to compress the thread against said thread engaging surface, and means for imparting a variable pressure to said member consisting of a member slidably mounted in the periphery of the thread case.

4. A locking thread mechanism for sewing machines comprising a cylindrical thread case, a centrally located thread outlet in said case, a thread engaging surface at the periphery of said outlet, a member adapted to compress the thread against said thread engaging surface and means for imparting a variable pressure to said member consisting of a member slidably mounted in the periphery of the thread case, and means for locking said slideable member comprising a positioning surface formed in said member and adapted to co-act alternatively with a plurality of positioning surfaces formed in said thread case.

5. A locking thread mechanism for sewing machines comprising a cylindrical thread case, a centrally located thread outlet in said case, a thread engaging surface at the periphery of said outlet, a member adapted to compress the thread against said thread engaging surface, and means for imparting a variable pressure to said member consisting of complementary, inter-engaging inclined surfaces, one of said surfaces being formed in said member and the other being formed in a member slidably mounted in the periphery of the thread case.

6. A locking thread mechanism for sewing machines comprising a cylindrical thread case, a centrally located thread outlet in said case, a thread engaging surface at the periphery of said outlet, a member adapted to compress the thread against said thread engaging surface and means for imparting a variable pressure to said member consisting of a member slidably mounted in the periphery of the thread case, and means for locking said slideable member comprising a projection formed in said member and adapted to engage alternatively a plurality of recesses formed in said thread case.

7. In a lockstitch sewing machine, the combination with an open ended tubular loop taker, of a stationary cylindrical thread case mounted in said loop taker, said thread case being open at its forward end and closed at its rear end to receive and hold tightly a thread cop passed through said loop taker and into said thread case, means for holding the thread cop in proximity to the wall of the thread case until entirely exhausted comprising an interlining of foil between the thread cop and the thread case, a centrally located thread outlet in said thread case, and means for applying tension to the thread.

8. In a lockstitch sewing machine, the combination with an open ended tubular loop taker of a stationary cylindrical thread case mounted in the loop taker open at its forward end for the reception of a thread cop inserted through the open end of the loop taker, means for holding the thread cop in proximity to the wall of the thread case until entirely exhausted comprising an interlining of foil between the thread cop and the thread case arranged to leave the thread delivery end of the cop free of foil, a centrally located thread outlet in said thread case through which the thread passes from the interior of the cop, and means for applying tension to the thread.
